UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A COAT.

Application filed July 21, 1925. Serial No. 14,158. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof.

Figure 1 is a front view of a coat, showing my new design.

Figure 2 is a three-fourths back view of the coat shown in Figure 1.

Figure 3 is a two-thirds front view of the

upper part of the coat shown in Figure 1, illustrating the front portion of the ornamental sleeve connection.

Distinctive features of my design are the zigzag formation at the juncture of the sleeve with the body of the coat shown in Figures 2 and 3, the extension of the upper edge of the sleeve up over the shoulder as indicated in Figures 2 and 3 as well as the novel design of the cuff, best shown in Figure 2 of the drawing.

I claim:

The ornamental design for a coat, as shown and described.

TAUBE DAVIS.
